A. F. STRAFUS

OIL CAN

Filed Aug. 5, 1926

FIG. 1

FIG. 4

INVENTOR.

ANTON F. STRAFUS

BY

R. W. Smith
ATTORNEY.

UNITED STATES PATENT OFFICE.

ANTON F. STRAFUS, OF LOS ANGELES, CALIFORNIA, ASSIGNOR OF ONE-HALF TO
LUTHER R. McGARVIN, OF LOS ANGELES, CALIFORNIA.

OIL CAN.

Application filed August 5, 1926. Serial No. 127,211.

This invention relates to the spout for an oil can or the like; and it is the object of the invention to provide an extremely simple but practical arrangement whereby swinging the spout will open or close its discharge bore and permit the oil can being stored in a restricted space when not in use.

It is a further object of the invention to securely retain the spout in either its open or closed position and still permit it being readily swung to the opposite position, the construction being adapted for use in connection with an oil can of standard design and providing for readily taking up wear in the pivotal bearing for the swinging spout.

The invention will be readily understood from the following description of the accompanying drawings, in which:

Fig. 1 is a perspective view with the spout of an oil can swung to closed position.

Fig. 2 is an axial section through an oil can with the spout swung to open position.

Fig. 3 is a perspective view of the spout.

Fig. 4 is a transverse section on the line 25 4—4 of Fig. 2.

The invention is applicable to any oil can or other container adapted for discharge of its contents through a spout, and the invention is illustrated in connection with an oil can 1 of standard design, having the usual threaded neck 2 upon which the spout is mounted.

The spout includes a closure means 3 threaded onto neck 2 and having an axial discharge bore 4, and a concave bearing seat 5 at the outer end of the closure means is adapted to receive a spout 6 which is held in place by a thimble 7, so that the discharge bore 8 of the spout may be swung into or out of alignment with the bore 4.

As an instance of this arrangement the inner end of spout 6 forms a spherical bearing 10 journaled in the concave seat 5, and the bore of the spout opens through the sphere 10 so that when the spout is swung into axial alignment with the closure means 3, the bores 4 and 8 are in alignment for discharge of the contents of can 1, and when the spout is swung at right angles to the axis of closure means 3 as shown in Fig. 1 and in dotted lines in Fig. 2, the bore of the spout is closed to the bore 4 by the sphere 10.

The thimble 7 is threaded onto the outer end

of the closure means 3 as shown at 11, and forms a concave bearing 12 received over the sphere 10, with the spout 6 projecting through an arcuate slot 13 in the side of the bearing and limited in its swing by the ends of the slot to position the spout in either closed or open position as shown in Figs. 1 and 2.

In assembling the parts the spout 6 is projected through slot 13 so as to seat the sphere 10 in bearing 12, and the thimble 7 is then threaded onto closure means 3 so as to journal the sphere 10 between the bearings 5 and 12. By tightening the threaded connection 11, wear is taken up so as to maintain a frictional engagement whereby the spout will be held against accidental displacement in any position to which it is swung, while still permitting the spout to be readily swung by hand to either open or close the bore of the spout.

When the spout is swung to closed position 75 the bore 4 is positively shut off by the sphere 10 to prevent leakage of oil, and swinging of the spout to angular position when closed, provides for conveniently storing the oil can in a space of limited height, a carpenter's tool-box, for example. The abutment formed by the end of slot 13 provides for exact alignment of the bore of the spout with the bore 4 when the spout is swung to open position, thereby providing for free and unobstructed 85 flow of oil.

I claim:

Closure means for an oil can having a discharge neck, comprising an integral member having a bore opening therethrough with 90 one end of the integral member forming detachable engaging means adapted to engage the neck of the oil can and the opposite end of the integral member being recessed to form a semi-spherical concave-bearing seat 95 surrounding the bore of the integral member, a spout having a spherical bearing member at its inner end with the bore of the spout opening through said spherical bearing member, the said spherical bearing member 100 being adapted to fit snugly in the semi-spherical concave bearing seat, and a thimble adapted to be received over the spherical bearing member and forming a concave semi-spherical bearing seat adapted for snug 105 engagement with the spherical bearing mem-

ber, the integral closure member being formed with means for detachably engaging the thimble so as to retain the spherical bearing member in snug engagement in its semi-spherical concave bearing seats with the bores of the spout and integral closure member adapted for alinement or non-alinement

by swinging the spout relative to the closure member, and the thimble having an arcuate slot for the projecting spout to permit said 10 swinging of the spout.

In testimony whereof he has affixed his signature to this specification.

ANTON F. STRAFUS.
